UNITED STATES PATENT OFFICE.

BOHN CHAPIN HICKS, OF MINNEAPOLIS, MINNESOTA, ASSIGNOR, BY
MESNE ASSIGNMENTS, TO THE HICKS STOCK CAR COMPANY, OF
CHICAGO, ILLINOIS.

DOUBLE-DECK STOCK-CAR.

SPECIFICATION forming part of Letters Patent No. 449,621, dated March 31, 1891.

Application filed February 17, 1890. Serial No. 340,786. (No model.)

To all whom it may concern:

Be it known that I, BOHN CHAPIN HICKS, a citizen of the United States, residing in Minneapolis, in the county of Hennepin and State 5 of Minnesota, have invented a new and useful Improvement in Convertible Double-Deck Stock-Cars, of which the following is a specification.

This invention relates to certain improvements in the construction of what are commonly known as "double-deck stock-cars," although some of its features may be used in stock-cars in which the double deck is not present. Its principal feature consists in the 10 combination, with a double-deck car in which the upper deck is removable and watering-troughs are also present, so that the car can be converted into an ordinary stock-car for cattle, of swinging brackets located in the 15 wall of the car above the watering-troughs and carrying planking, which, when the brackets are in their normal position, will serve as a part of the upper deck and also as a lid or cover for the watering-troughs.

20 The invention further consists in the novel construction and combination of the several parts hereinafter fully set forth, and particularly pointed out in the claims.

In the accompanying drawings, which form 25 a part of this specification, Figure 1 is a transverse vertical section of a car to which my present improvements have been applied. Fig. 2 is a view in perspective of the outside of the car, showing the hinged lid carrying brackets swung outward, so as to uncover the watering-troughs.

In the drawings, A represents the wall of the car, B the removable upper deck, and C the watering-troughs. Pivoted in the wall of the 30 car at d are a series of short brackets D, which carry the planking E, and which latter, when in their normal position, (indicated by the full lines at Fig. 1,) are located immediately above the watering-troughs, so 35 as to form covers therefor. Said planking also serves when in said position as a part of the upper deck, as is apparent from the drawings.

When the car is to be converted into a cattle-car, the deck B is removed, and the brackets 40

55 D may then be swung outward to the position shown by the broken lines at Fig. 1 and in full lines at Fig. 2 whenever the cattle need be watered. The mechanism by which the brackets are swung outward in this manner consists of the lever F, joined to an eccentric f at the end of the car, and connections from such eccentric to the brackets at either side of the car, so that both may be operated simultaneously by said lever F. These connections 60 preferably consist of connecting-rods G, levers gg', shaft G', links H, and studs h on the brackets. The brackets at each side of the car may also carry the outside slats i, and all of them upon one side of each half of the car, being 65 united by these slats and by the planking E, of course move together. When the brackets are to be returned to their normal position, the lever and eccentric are simply reversed, and they then lock the parts so that the cattle 70 cannot push them out. The beltry-rails J, by which the cross-bars L of the upper deck are supported, are located in front of the trough-lids or planking E and serve as a further security to the lids against being dislodged by 75 the stock.

I claim—

1. In a stock-car, the side posts thereof, watering-troughs located between said side posts, and a removable upper deck located 80 when in position for use in substantially the same horizontal plane as said troughs, in combination with brackets pivoted between each pair of side posts, the pivotal points of said brackets being located above said 85 troughs and said brackets being so pivoted that their lower ends swing outwardly, each pair of brackets carrying at their lower ends a plank or lid which when said brackets occupy their normal position serves both as a 90 cover for the trough therebeneath and as an extension between the side posts of the upper deck, said brackets being capable of swinging outwardly far enough to uncover said troughs, substantially as set forth. 95

2. In a stock-car, the side posts thereof, watering-troughs located between said side posts, and a removable upper deck located 100 when in position for use in substantially the same horizontal plane as said troughs, in com-

bination with a pair of brackets pivoted between each pair of side posts, the pivotal points of said brackets being located above said troughs and said brackets being so pivoted that their lower ends swing outwardly, each pair of brackets carrying at their lower ends a plank or lid which when said brackets occupy their normal position serves both as a cover for the trough therebeneath and as an extension between the side posts of the upper deck, said brackets being capable of swinging outwardly far enough to uncover said troughs, and said brackets carrying slats *i i*, which constitute when the brackets are in their normal position part of the exterior boarding of the car, substantially as set forth.

3. In a stock-car, the side posts thereof, watering-troughs located between said side posts, and a removable upper deck located when in position for use in substantially the same horizontal plane as the said watering-troughs, in combination with a pair of brackets pivoted between each pair of side posts, the pivotal points of said brackets being located above said troughs, and said brackets being so pivoted that their lower ends swing outwardly, each pair of brackets carrying at their lower ends a plank or lid which when said brackets occupy their normal position serves both as a cover for the trough therebeneath and as an extension between said side posts of the upper deck, said brackets being capable of swinging outwardly far enough to uncover said troughs, and longitudinal slats *i i*, extending along the sides of the car, said slats being secured to the outer edges of a plurality of said pairs of brackets, whereby said slats perform a threefold function, to wit: first, they constitute when the brackets are in their normal position a portion of the side walls of the car; second, they enable a plurality of the pairs of brackets to be operated simultaneously, and, third, they constitute stops to prevent the inward swinging of the brackets, substantially as set forth.

4. In a stock-car, the side posts thereof and watering-troughs located between said side posts, in combination with outwardly-swinging covers or lids, one for each of said troughs,

each cover or lid being pivotally connected with and between two of the side posts, a longitudinal shaft journaled along the side of the car and common to a plurality of said lids or covers, a plurality of crank-arms on said shaft, and links connecting said crank-arms and said lids or covers, substantially as set forth.

5. In a stock-car, the side posts on opposite sides thereof, watering-troughs located between said side posts on both sides of the car, and a removable upper deck located when in position for use in substantially the same horizontal plane as said troughs, in combination with a pair of brackets pivoted between each pair of side posts, the pivotal points of said brackets being located above said troughs and said brackets being so pivoted that their lower ends swing outwardly, each pair of brackets carrying at their lower ends a plank or lid which when said brackets occupy their normal position serves both as a cover for the trough therebeneath and as an extension between said side posts of the upper deck, said brackets being capable of swinging outwardly far enough to uncover said troughs, longitudinal slats *i i*, extending along each side of the car, said slats on each side of the car being secured to the outer edges of a plurality of said pairs of brackets, whereby said slats perform a threefold function, to wit: first, they constitute when the brackets are in their normal position a portion of the side walls of the car; second, they enable a plurality of the pairs of brackets to be operated simultaneously, and, third, they constitute stops to prevent the inward swinging of the brackets, a longitudinal shaft *G'* on each side of the car, a plurality of crank-arms *g'* on each shaft, a plurality of links *H*, connecting said crank-arms and said brackets, an operating-wheel *f* on the end of the car, crank-arms *g* on the end of each shaft, and links *G*, connecting said crank-arms *g* with said wheel *f*, substantially as set forth.

BOHN CHAPIN HICKS.
